UNITED STATES PATENT OFFICE

2,663,250

TOOL FOR REMOVING ADDRESS-O-GRAF
TYPE STRIPS

George W. Schaefer, Quincy, Mass.

Application June 4, 1952, Serial No. 291,761

3 Claims. (Cl. 101—1)

1

The type for Address-o-graph plates is formed on one or more thin metal strips carried by a backing plate, the backing plate being provided with guide elements engaging about the side edges of the printing strips and one or more spring latches securing the strips against endwise removal. As the printing material becomes obsolete, these metal type strips may be removed and replaced by new ones, the backing plates being still usable. The backing plates also commonly carry paper strips showing in usual printed form the subject matter contained on the type strip, which is in reverse. Since during use the plates, and more particularly the parts carrying the type strips, are coated with ink, the removal of the strips by hand is a disagreeable and dirty job.

The present invention, therefore, relates to a tool by which the removal of the type and paper strips is facilitated and by which much of the soiling of the hands heretofore associated therewith may be avoided.

The tool of the present invention, therefore, provides means actuatable to release the type strip securing latch at one end and to engage the opposite end to exert removing pressure thereon while the latch is held released.

For a complete understanding of this invention reference may be had to the accompanying drawings in which

Figure 1 is a side elevation of a tool embodying the invention.

Figure 2 is a top plan view of the same.

Figure 3 is a detail sectional view on line 3—3 of Figure 1.

Figure 4 is a top plan view of an Address-o-graph plate showing a printing strip held thereto.

Figure 5 is a detail sectional view on line 5—5 of Figure 4 and showing the tool of Figures 1 and 2 initially presented thereto.

Figure 6 is a view similar to Figure 5 but showing the tool engaging the type strip which has been partially removed from the plate.

Figure 7 is a view similar to Figure 4 but showing a plate with a pair of type strips carried thereby.

Figure 8 is an inverted plan view of a tool formed to remove simultaneously both type strips from a plate of the construction of Figure 7.

Figures 9 and 10 are detail sectional views on lines 9—9 and 10—10, respectively, of Figure 8.

Figure 11 is a side elevation of a tool modified to remove type strips from the plate shown in Figure 13.

Figure 12 is a detail sectional view on line 12—12 of Figure 11.

2

Figure 13 is a plan view of a plate having three type strips and showing the paper identifying strip also in position.

Figures 14 and 15 are views similar to Figure 6, but showing the tool removing the long and short type strips, respectively, from the plate of Figure 13.

Figure 16 is a detail sectional view on line 16—16 of Figure 13 and showing a tool part engaging beneath the paper strip preparatory to its removal from the plate.

Referring first to Figure 4, there is shown an Address-o-graph plate 1 having struck upwardly therefrom fingers 2 which are bent to embrace one edge portion of a printing or type plate 3. The opposite edge portion of this type plate is guided by a single marginal finger 4 integral with the plate 1. The backing plate is also provided with one or more spring latches 5. These latches are formed between slots 6 through the backing plate which form tongues, the outer ends 7 of which are turned upwardly and outwardly so as to normally engage beyond and adjacent to one of the ends of the type strip 3. As shown in Figure 4 such a spring latch is positioned at each end of the type strip and these latches normally hold the type strip in position.

There may also be other fingers 8 struck upwardly from the backing plate 1 which cooperate with a single marginal finger 9 to hold a paper strip upon which is printed the information which is contained on the type strip, but since the type strip is used for printing the characters and the letters are therefore reversely positioned, the paper strip gives the same information in a more legible form. Such a paper strip is shown in Figure 13 at 10.

The tool of the present invention comprises a body portion 15 having a pair of spaced feet 16 and 17. The foot 16 has secured to its under face a channel-shaped element 18 having a channel portion 19 and an inwardly extending heel portion 20. This channel-shaped member may be engaged over the edge of the backing plate 1 as shown in Figure 5 while the tool is upwardly inclined as there shown, and in this position the heel 20 extends over the upturned end 7 of one of the latches 5. The other foot 17 has secured thereto a pusher element 21, which as shown, may have a longitudinal groove 22 in its forward edge which may be engaged with the opposite end of the type strip in the position shown in Figure 6.

When the tool is rocked down from the position of Figure 5 to such engaging position of Figure 6, the heel 20 of the channel element depresses the

latch beneath the end of the printing strip 3 so that by moving the tool lengthwise of the printing strip toward the depressed latch 5, the entire printing strip is moved bodily over the depressed latch and may be removed entirely from the backing plate, it being shown partly removed in Figure 6.

The tool 15 may be provided with a recessed side face as at 25 to facilitate engagement by the fingers of the user exerting the endwise pressure thereon which is necessary to remove the printing strip.

The pusher element 21, as shown best in Figure 3, may be provided with a central notch 27 which will permit this element to pass over the latch 7 at the adjacent end of the printing strip as the printing strip is being removed.

In Figures 7 and 8 a modified construction of backing plate is shown in which a pair of parallel printing strips 3a are employed each having its own spring latch 5 at opposite ends with suitable guide fingers 2a and 4a for the side edges of the printing strips and guide fingers 3 and 9 to receive the paper strip.

With this arrangement the latch-depressing and strip-pushing elements are somewhat differently formed as shown in Figures 8, 9 and 10. The latch-depressing element comprises the channel-shaped member 18a provided with a central slot 28 positioned to clear the fingers 2a between adjacent edges of the printing strips. It has a heel portion 29a of sufficient length to engage both of the spring latches at one end of the two strips. The pusher element 21a is provided with three transverse notches 30 in order to clear the latches 5 which are not engaged and depressed by the element 29a and also to clear the central guide fingers 2a.

In Figure 13 there is shown a still different form of back plate having three printing type strips 35 and 36, the type strips 35 being shorter than the type strips 3 and 3a previously shown, and the type strip 36 being of somewhat more than double the widths of the strips 35 and positioned beyond the inner ends of each of the strips 35. This backing plate 15 is provided with a spring latch 5 opposite the outer end of each of the type strips 35 and a fixed stop lug 37 at the inner end of each of these type strips, and which also cooperates with the inner end of the strip 36. The strip 36 has a single spring latch 5 outwardly of its outer edge. All these strips are held between fingers 2 and 4 pressed up from the backing plate.

It will be noted that the tool 15 has been shown in all the figures as having a foot 40 intermediate to the feet 16 and 17, and for operation on the plate of Figure 13 this foot 40 is used, together with the feet 16 and 17. Each of the feet 16 and 17 has a channel-shaped latch-depressing element 18b and the intermediate foot 40 is provided with a pusher element 45. The channel elements 18b are each provided with the heel portion 29b, this channel portion 18b on the foot 16 and the pusher element 45 cooperating to remove the printing strips 35, and the channel member 18b on the foot 17 and the pusher element 45 cooperating to remove the printing strip 36, as shown in Figures 14 and 15, respectively. The method of operation is similar to that previously described, the heel 29b acting to depress the spring latch at the outer end of the printing strip when the presser member 45 is pushed downwardly behind the inner end of the printing strip, whereupon by moving the tool in the proper direction

the printing strip may be pushed over the depressed latch and removed. These elements may be notched as required to clear the fingers 2 and the stops 37, and the pusher element 45 may be similarly notched on its lower face as shown in Figure 12.

The tool may also have a rod 48 extending upwardly therefrom and provided with a tapered outer end 49, which may be inserted beneath one end of the paper strip 10 and lift it where it may be grasped by the fingers for easy removal as shown in Figure 16. The paper strip may normally rest between stop lugs 50 pressed upwardly from the backing plate, there being however sufficient room at one side thereof for the insertion of the end of the rod 48.

From the foregoing description of certain embodiments of this invention it will be evident to those skilled in the art that various changes and modifications may be made without departing from its spirit or scope.

I claim:

1. A tool for removing a type strip from a backing plate, said backing plate having a depressible spring latch normally projecting above and at one end of said strip and preventing removal thereof, said tool having a pair of spaced feet, one of said feet having a channel element adapted to engage about the edge of said backing plate and having a heel portion adapted to engage the top of said spring latch, the other foot having a pusher element spaced from said channel element to engage the opposite end of said type strip, said channel element heel portion being inclined downwardly and inwardly when said pusher element is positioned to engage said opposite end and depressing said spring latch below said strip, whereby on moving said tool lengthwise of said printing strip toward said latch said printing strip may be slid over said latch and be detached from said backing plate.

2. A tool for simultaneously removing a pair of parallel type strips from a backing plate, said backing plate having a depressible spring latch normally projecting above and at one end of each of said strips and having guide fingers extending up and embracing the side edges of said strips, said tool having a pair of spaced feet, one of said feet having a channel element adapted to engage about the edge of said backing plate between said guide fingers and having a heel portion adapted to engage the tops of said spring latches, the other foot having a pusher element spaced from said channel element to engage the opposite ends of said type strips between said guide fingers, said channel element heel portion being inclined downwardly and inwardly when said pusher element is positioned to engage said opposite ends and depressing said spring latches below said strips, whereby on moving said tool lengthwise of said printing strips toward said latch said printing strips may be slid over said latches and be detached from said backing plate.

3. A tool for simultaneously removing a pair of parallel type strips from a backing plate, said backing plate having a depressible spring latch normally projecting above and at one end of each of said strips and having guide fingers extending up and embracing the side edges of said strips, said tool having a pair of spaced feet, one of said feet having a channel element adapted to engage about the edge of said backing plate and having a heel portion adapted to engage the tops of said spring latches, the other foot having a pusher element spaced from said channel ele-

ment to engage the opposite ends of said type strips, said channel element heel portion being inclined downwardly and inwardly when said pusher element is positioned to engage said opposite ends and depressing said spring latches below said strips, whereby on moving said tool lengthwise of said printing strips toward said latch said printing strips may be slid over said latches and be detached from said backing plate, at least one of said elements being notched on its lower face to clear said guide fingers as said tool is moved to remove said strips. 10
